UNITED STATES PATENT OFFICE

165,265

GLASS VASE OR SIMILAR ARTICLE

Charles W. Carlson, Tiffin, Ohio

Application March 9, 1951, Serial No. 14,443

Term of patent 14 years

(Cl. D36—8)

To all whom it may concern:

Be it known that I, Charles W. Carlson, a citizen of the United States, residing in Tiffin, Ohio, have invented a new, original, and ornamental Design for a Glass Vase or Similar Article, of which the following is a specification, reference being had to the accompanying drawing, forming part thereof.

In the drawing,

Fig. 1 is an elevational view of a glass vase showing my new design; and

Fig. 2 is a horizontal cross-sectional view on the line II—II of Fig. 1.

The dominant features of the design reside in the part drawn in full lines, as shown.

I claim:

The ornamental design for a glass vase or similar article, as shown and described.

CHARLES W. CARLSON.
